FOREIGN PATENT DOCUMENTS

GB 2242695 9/1990

Primary Examiner — Susan E Krakower

Assistant Examiner — Beena Patel

(57) **CLAIM**

The ornamental design for a recovery anchor as shown and described.

DESCRIPTION

FIG. 1 is a front view of a recovery anchor showing my new design;

FIG. 2 is a rear view of the recovery anchor;

FIG. 3 is a right side view of the recovery anchor;

FIG. 4 is a left side view of the recovery anchor;

FIG. 5 is a top view of the recovery anchor;

FIG. 6 is a bottom view of the recovery anchor;

FIG. 7 is a top front side perspective view of the recovery anchor; and,

FIG. 8 is a top front side perspective view of the recovery anchor in an alternative position.

1 Claim, 7 Drawing Sheets
